(57) **CLAIM**

The ornamental design for a therapy device, as shown and described.

DESCRIPTION

FIG. 1 is a front perspective view of a therapy device showing my new design;

FIG. 2 is a front elevation view thereof, the back elevation view and side elevation views being identical thereto;

FIG. 3 is a top view thereof;

FIG. 4 is a bottom view thereof;

FIG. 5 is a front perspective view of a first alternative embodiment thereof;

FIG. 6 is a front elevation view of a first alternative embodiment, the back elevation view and side elevation views being identical thereto;

FIG. 7 is a top view of the first alternative embodiment thereof;

FIG. 8 is a front perspective view of a second alternative embodiment thereof;

FIG. 9 is a front elevation view of a second alternative embodiment, the back elevation view and side elevation views being identical thereto;

FIG. 10 is a top view of the second alternative embodiment thereof;

FIG. 11 is a front perspective view of a third alternative embodiment thereof;

FIG. 12 is a front elevation view of a third alternative embodiment, the back elevation view and side elevation views being identical thereto; and,

FIG. 13 is a top view of the third alternative embodiment of my new design for a therapy device.
